LESTER B. CHISHOLM, OF MELROSE, MASSACHUSETTS, ASSIGNEE TO EVERLASTIK, INC., OF CHELSEA, MASSACHUSETTS, A CORPORATION OF MASSACHUSETTS.

WOVEN ELASTIC FABRIC.

Application filed May 15, 1926. Serial No. 109,285.

The object of the invention is to obtain in a woven elastic fabric increased liveliness, softness and pliability, and especially to provide that the normal action of the elastic 5 shall in so far as possible be retained and not be made dull or sluggish by interference of the warp threads used in giving body to the fabric.

The invention can best be seen and understood by reference to the drawings in which—

Figure 1 is a conventional plan in enlarged detail of a woven elastic fabric embodying the invention, the web being shown 15 stretched to the limit as it is when woven, and

Fig. 2 is a plan the same as Fig. 1 excepting that the web is shown partially contracted.

20 In the drawings:—

1, 2, 3, 4 and 5 indicate a number of elastic warp strands representative of those in the woven fabric. These strands are all wound or covered elastic strands like those 25 customarily employed in an elastic woven fabric.

6, 7, 8, 9 and 10 indicate a number of wefts or picks which cross the elastic strands at the back and are representative of the 30 picks in the woven structure.

Each elastic warp strand is bound to all the picks by a "leno" thread 11 which passes alternately back and forth over the strand and laps under alternate picks on opposite 35 sides of the strand.

12, 13, 14 and 15 indicate binder warp threads representative of those in the woven structure. These threads are interwoven 40 with the pick to lie between each pair of elastic strands. They are all excessively hard twisted threads; a twist about three times the normal warp twist is preferably employed.

Of these threads, the threads 12 and 14 are right-twisted threads and the threads 13 and 15 are left-twisted threads. The threads are arranged in such manner that a right-twisted thread will alternate with a left-twisted thread in a direction lengthwise the picks. In other words, it 45 will be observed that the right-twisted thread 12 is followed by a left-twisted thread 13 and a right-twisted thread 14 is followed by a left-twisted thread 15. The right and left twisted threads pass respectively over and under alternate picks, that

is, the right-twisted warp threads 12 and 14 pass over the picks 6, 8 and 10 and under the picks 7 and 9, while the left-twisted warp threads 12 and 14 pass over the picks 7 and 9 and under the picks 6, 8 and 10. 60

In consequence, when the web contracts the binder warp threads being twisted so hard that they cannot be compressed, kink and automatically curl with displacement to the right and left along the picks. The 65 right-twisted threads 12 and 14 will swing to the left where they pass over the picks and to the right where they pass under the picks, while the left-twisted threads will swing to the right where they pass over the 70 picks and to the left where they pass under the picks.

An elastic webbing thus formed possesses peculiarly desirable properties. The binder warp will not interfere in the sense of lessening or dulling any normal or proper stretch of the elastic strands especially at the beginning of their action inasmuch as the bending or curling of the binder warp threads when the elastic strands are contracted displaces the binder warp threads laterally away from the elastic strands, the binder warp threads only interfering to prevent more than a proper or normal stretch of the elastic. As there is no compression 75 of the binder thread and hence no friction between the fibres, the web has unusual life or "kick" and comes back hard against the filling or pick. The web is also peculiarly soft and pliable owing to the flexible character of the binder warp especially when the web is contracted, and the fact that the binder warp then has only loose engagement 80 with the respective picks or filling. 85

Having thus fully described my invention, 90 I claim and desire to secure by Letters Patent of the United States:—

1. In a woven elastic fabric, the combination comprising elastic warp strands, picks, and binder warp threads woven 100 through the picks in the space between the elastic strands, said binder warp threads being sufficiently hard twisted to kink and automatically curl with lateral displacement away from the elastic strands when the elastic strands are contracted to an amount permitted by the drawing together of the picks. 105

2. In a woven elastic fabric, the combination comprising elastic warp strands, 110

5 picks, and binder warp threads woven through the picks in the space between the elastic strands, said binder warp threads being sufficiently hard twisted to kink and 10 automatically curl with lateral displacement to the right and left along the picks away from the elastic strands when the elastic strands are contracted to an amount permitted by the drawing together of the picks, 15 certain of said binder warp threads having a right twist and certain of said binder warp threads having a left twist.

3. In a woven elastic fabric, the combination comprising elastic warp strands, 15 picks, and binder warp threads woven through the picks in the space between the

elastic strands, said binder warp threads being sufficiently hard twisted to kink and automatically curl with lateral displacement to the right and left along the picks away 20 from the elastic strands when the elastic strands are contracted an amount permitted by the drawing together of the picks, certain of said binder warp threads having a right twist and certain of said binder warp 25 threads having a left twist, said right and left twisted binder warp threads being alternately arranged in the weave and being woven to cross over and under, respectively, alternate picks.

LESTER B. CHISHOLM.
